SPARK PLUG ELBOW AND BARREL SEALING
GROMMETJohn D. Frazee, Glastonbury, Conn., assignor to
United Aircraft Corporation, East Hartford,
Conn., a corporation of Delaware

Application February 9, 1950, Serial No. 143,265

6 Claims. (Cl. 174—77)

1

This invention relates to an improvement in electrical connections and refers particularly to an improved connection between a spark plug and an ignition cable of an internal combustion engine.

An object of this invention resides in the provision of a connection between the spark plug and ignition cable which is detachable and re-wireable. This permits easy replacement of parts since detail parts may be removed and replaced. This replacement of detail parts reduces the expense necessary to keep an ignition system in the best of condition since whole assemblies need not be discarded when only a small part thereof actually needs replacing.

A further object resides in the provision of an improved union between the ignition cable and spark plug which includes a resilient grommet which provides an effective seal against moisture entering the spark plug cylinder from the ignition harness. This grommet also seals the spark plug from electrical flashover. The use of a corona shield in said grommet tends to reduce the formation of corona.

In the drawing,

Fig. 1 is an elevation view partly in section of an internal combustion engine spark plug, and part of an ignition shield connected by an elbow construction embodying the present invention.

Fig. 2 is a view partly in section showing a modification of the grommet.

Referring to the drawings in detail, the spark plug generally indicated at 2 is of the conventional type in common use on aircraft engines and consists of one part.

The spark plug 2 has at its lower end an external threaded portion 6 adapted to be screwed into an internally threaded aperture in an engine cylinder, and a polygonal wrench receiving portion 8. Ground electrodes 10 are made integral with said spark plug so that when the spark plug is in its engine operating position they extend down into the engine cylinder.

The upper end of the spark plug 2 is formed as a metallic cylinder 14 externally threaded at 16. Fixed within the spark plug is the spark plug core including a metal electrode 18 and insulating material. This metal electrode 18 fits into the lower end of the spark plug to form gaps with ground electrodes 10. The insulating material referred to above is used to prevent electrical contact between the metal electrode 18 and any part of the spark plug 2, it consists of material immediately surrounding the metal electrode 18 as at 20 and a coating around the

2

inner side of the cylinder 14 shown at 22. The end of the electrode 18 within the cylinder 14 is peened over the contact button 19 as at 21.

The spark plug elbow 24 used to protect the insulated cable 26 as it bends near the spark plug, consists of an elbow 28 having a ferrule attached on each end such as by silver soldering or brazing. This ferrule may be formed integral with said elbow if desired. The ferrule 30 on one end is externally threaded at 32 and has a countersunk portion 34 the purpose of which is to be disclosed hereinafter. The ferrule 36 on the opposite end has a flange 38 for engaging a cooperating flange 40 on a union nut 42, internally threaded at 44, which is placed over the elbow before the ferrules are attached. This union nut 42 cooperates with the externally threaded upper end 16 of the cylinder 14 to provide a rigid connection between the spark plug elbow 24 and the spark plug 2.

The ignition shield 48 of the harness consists of a flexible metallic tube 50 having a ferrule 52 attached to one end such as by silver soldering or brazing. Said ferrule having a flange 54 for engaging a cooperating flange 56 on a union nut 58, internally threaded at 60, which is placed over the tube before the ferrule is attached. This union nut 58 cooperates with the externally threaded part 32 of ferrule 30 to provide a rigid connection between the ignition shield 48 and the spark plug elbow 24. The other end of the shield may be attached to a harness by any means desired.

The insulated cable 26 referred to above is a lead-in from an electrical source (not shown) and consists of a conductor 62 coated with a resilient insulated covering 64. One end (not shown) is attached within a harness, by any means desired, to the electrical source referred to above. The other end of the conductor at 66 is inserted in a hole 68 in a metal stud 70. The stud is held on the wire by being crimped at 72. The metal stud 70 has a flanged portion 74 of the same diameter as the insulated covering 64 of the conductor 62. This flange 74 fits against the covering 64. The remainder of the stud is externally threaded at 76 to provide a means for attaching said cable to form an electrical contact and hold it in place in a manner to be described hereinafter.

A grommet 78 within the spark plug elbow 24 and upper part of the cylinder 14 of the spark plug 2 is a member formed as a tube of resilient material. The outside portion within 55 the spark plug elbow 24 fits tightly from a recess

80 in ferrule 36 to the countersunk portion 34. This portion may be sealed with a cement to further insure against moisture leakage from the harness. This part of the grommet within said elbow also provides extra insulation against heat. A flange 82 on the grommet fits in the recess 80 and is held therein in its assembled position between that end of the elbow and the top of cylinder 14 of the spark plug. This flange 82 seals the spark plug 2 from moisture leakage and serves to prevent the grommet 78 from being blown out in the event of gas leakage through said spark plug. The flange also governs the amount of the grommet which extends into elbow 24 and into cylinder 14.

The outside portion of the grommet within the cylinder 14 has a diameter smaller than the diameter of the cylinder and is provided with sealing rings 84 which form a seal with the cylinder 14. The relief in the areas between the sealing rings 84 prevents the grommet 78 from sticking to the inside of the spark plug cylinder 14. The sealing rings 84 seal the spark plug cylinder from electrical flashover to the top of the cylinder.

The inside portion of the grommet within the elbow fits tightly around the cable 26 passing through the elbow. This tight fit seals against the passage of moisture into the spark plug and the escaping of gas vapor through the spark plug cylinder. The inside portion within the cylinder contains a circular flange 86. The cable 26 also fits tightly within this inside portion up to said flange. The threaded portion 76 of the stud 70 on the end of the cable extends through said flange for a purpose to be described hereinafter.

A skirt 88 is formed below the flange 86. A metallic cup 90 fitting within said skirt and having a hole 92 in the bottom thereof for allowing the threaded portion 76 of stud 70 to extend through may be inserted into said skirt. This copper or brass corona shield lowers the voltage stress to the surrounding air by increasing the effective area of the conductor and thereby reducing the formation of corona. A spring 94 and spring retainer 96 is provided to make a good electrical contact between the stud 70 and electrode 18 of the spark plug. The spring 94 may be fixed on the internally threaded spring retainer 96 by any means available as long as an electrical contact is made therebetween. The threaded portion 76 of the stud 70 screws into the spring retainer 96. This provides an electrical contact between the stud 70 and spring retainer 96. The flange 86 compressed therebetween holds the cable 26 and spring 94 in place. The spring in its extended position is longer than the skirt 88, as shown in Fig. 2, so that a positive contact is made with the electrode 18.

The length of the grommet 78 disassembled, from the flange 82 to the bottom of the skirt 88, is longer than the depth of the cylinder 14 from its top to the top of the insulating material 20 around the electrode 18, so that the lower edge of said skirt is forced against the insulating material around said spring and contact button 19 forming a seal when the grommet is in its assembled position.

A second grommet 100 within the shield 48 is also a member formed as a tube of resilient material. On one end is a flange 102 tapered to fit into the countersunk portion 34 of the ferrule 36 of the spark plug elbow 24. The other end fits tightly into the shield 48 with the cable 26 also fitting tightly as it passes therethrough. The flange 102 is held between the face of the counter-

sunk portion 34 of the elbow 24 and the cooperating end of the ferrule 52 of the cable 48. This grommet 100 aids in preventing grommet 78 from being forced out of the elbow 24 by leakage of gas through the spark plug 2.

Fig. 2 is a modification of the grommet 78 as shown in Fig. 1. This grommet 104 differs from grommet 78 mainly in the connecting and holding means used to make an electrical connection between the conductor 62 of cable 26 and spring 94, and to hold the cable 26 and spring 94 in place.

This modification has in place of the single flange 86 in grommet 78, a flange 106 with a molded-in insert 108 below it. Said insert has an internally threaded bore 110 adapted to receive the threaded end 76 of stud 70, and an externally threaded boss 112 which extends into skirt 88 adapted to screw into a spring retainer 96.

The connection as shown in Fig. 1 can be assembled by one of two methods, depending on whether or not the connection is being made while the harness is apart or while the harness is on the engine. The method of assembling the connection, considering the harness to be on the engine, is as follows:

The ignition shield 48 is slipped over the cable 26, which is attached within the harness and extends out therefrom, and attached to the harness by any means desired. Then the grommet 100 is slipped over the conductor 26 and into the ignition shield 48. The cable 26, with its metal stud 70 on the end, is inserted through the spark plug elbow 24, and pulled through as far as it will go. The cable is made so that a few inches are provided within the harness to permit the cable to be extended that distance over the minimum length necessary in its assembled position. Then the cable 26 is inserted in the grommet 78 until the externally threaded portion 76 of stud 70 extends through the flange 86 into skirt 88. The spring retainer 96 is screwed on stud 70 with spring 94 attached. The grommet 78 is then pulled back into the spark plug elbow 24 until flange 82 on the grommet fits in recess 80 in ferrule 36. Then the spark plug elbow 24 and ignition shield 48 are connected rigidly together by the means provided and disclosed hereinbefore. The end of the grommet 78 projecting from the elbow 24 is then inserted in the cylinder 14 of a spark plug 2. The spark plug elbow 24 and spark plug 2 are then rigidly connected together by the means provided and disclosed hereinbefore. If a cement is to be used, for example as referred to above, it can be put on at any time before the parts to be placed together are finally positioned.

The only difference between the method disclosed above and the method using the grommet 104 of Fig. 2, is that the spring retainer 96 need not be installed before the grommet is drawn into the spark plug elbow 24 since the cable 26 is held in the grommet by the molded-in insert 108. The spring retainer 96 and spring 94 can be put in place anytime before the grommet is inserted into the spark plug cylinder 14.

The method of assembling the connection, considering the harness to be apart, is as follows:

The cable 26, with its metal stud 70 on the end, is inserted into the grommet 78 until the externally threaded portion 76 of the stud 70 extends through the flange 86 into skirt 88. The spring retainer 96 is screwed on stud 70 with spring 94 attached. The free end of cable 26 is then inserted into spark plug elbow 24 and pulled

from the opposite end until flange 82 on the grommet fits in recess 80 in ferrule 36. Then the grommet 100 is slipped over the free end of the cable 26 and pushed down until the tapered flange 102 fits against the countersunk portion 34 of ferrule 30. The free end of the cable 26 is then inserted into the ignition shield 48 and drawn through until the end of ferrule 52 fits against the flat side of the tapered flange 102. The spark plug elbow 24 and ignition shield 48 are then connected rigidly together by the means provided and disclosed hereinbefore. The remaining two steps of this method are identical to the last two steps of the other methods described above.

Here again, the only difference between the method disclosed immediately above and the method using the grommet 104 of Fig. 2, is that the spring retainer 96 need not be installed before the grommet 104 is drawn into the spark plug elbow 24 since the cable 26 is held in the grommet 104 by the molded-in insert 108. The spring retainer 96 and spring 94 can be put in place any time before the grommet is inserted into the spark plug cylinder 14.

While a suitable mechanical embodiment in two slightly different forms has been hereinabove described and illustrated in the accompanying drawing for the purpose of disclosing the invention, it is to be understood that the invention is not limited to the particular embodiment so illustrated and described, but that such changes in the size, shape and arrangement of the various elements and of the materials of which they are formed may be resorted to as come within the scope of the subjoined claims.

Having now described the invention so that others skilled in the art may clearly understand the same, what it is desired to secure by Letters Patent is as follows:

1. A grommet for use in a connection between a spark plug having a cylinder provided with an internal seating surface and an adjacent connector, said grommet consisting of a sleeve of resilient material for projection in part into said connector and in part into said cylinder, said sleeve having an external flange, said flange being adapted to be held between said connector and said cylinder, the portion of the sleeve adapted for projection within said connector being adapted dimensionally to have a slidable fit in the connector, the portion of the sleeve adapted for projection into said cylinder having a sealing ring adapted dimensionally to have a slidable fit in the cylinder, a part of the sleeve below said ring forming a skirt, the length of said portion adapted for projection into said cylinder being adapted dimensionally so that it is longer than the inner depth of the cylinder to the seating surface so that when said last named portion is in its assembled position the lower edge of said skirt is adapted to be forced against the seating surface of said cylinder forming a seal.

2. In combination, a cylinder provided with an internal seating surface, an electrical contact member located on said seating surface, a grommet including a sleeve of resilient material projecting in part into said cylinder, said sleeve having a flange determining the portion thereof extending into said cylinder, means for holding said flange against the open end of said cylinder, the part of the sleeve projecting into said cylinder having a sealing ring thereon, said sealing ring having a slidable fit against said cylinder, the end of said sleeve projecting into said cylinder,

der being deformably positioned against the seating surface of said cylinder and forming a seal around said contact member.

3. In combination, a cylinder provided with an internal seating surface, an electrical contact member located on said seating surface, a connector connected to the open end of said cylinder, a grommet consisting of a sleeve of resilient material projecting in part into said connector and in part into said cylinder, said sleeve having a flange determining the portions thereof extending respectively into said connector and cylinder, said flange being held between said connector and said cylinder, the part of the sleeve projecting into said cylinder having a slidable fit therein, the part of the sleeve projecting into said cylinder having a sealing ring thereon, said sealing ring having a slidable fit in said cylinder, the end of said sleeve projecting into said cylinder being forced against the seating surface of said cylinder forming a seal around said contact member.
4. A grommet for use in a spark plug having a cylinder provided with an internal seating surface, including a sleeve of resilient material for projection into said cylinder, said sleeve having sealing rings, said sealing rings adapted dimensionally to have a slidable fit against the sides of the cylinder, and the end of said sleeve adapted to project into said cylinder being adapted to be deformably positioned against said seating surface to provide a seal with said seating surface.

5. In combination, a cylinder provided with an internal seating surface, an electrical contact member located on said seating surface, a connector connected to the open end of said cylinder, a grommet consisting of a sleeve of resilient material projecting in part into said connector and in part into said cylinder, said sleeve having a flange determining the portions thereof extending respectively into said connector and cylinder, said flange being held between said connector and said cylinder, the part of the sleeve projecting into said connector having a slidable fit therein, the part of the sleeve projecting into said cylinder having a sealing ring thereon, said sealing ring having a slidable fit in said cylinder, the end of said sleeve projecting into said cylinder being forced against the seating surface of said cylinder forming a seal around said contact member, an insulated conductor extending into said grommet, and means for making contact between the end of said conductor in said grommet and said contact member.

6. In combination, a spark plug having a cylinder provided with an internal seating surface, an electrical contact member located on said seating surface, a tube, a connector connecting said cylinder to said tube, a first grommet consisting of a sleeve of resilient material projecting in part into said connector and in part into said cylinder, said sleeve of said first grommet having a flange determining the portions thereof extending respectively into said connector and cylinder, said flange being held between said connector and said cylinder, the part of the sleeve projecting into said connector having a slidable fit therein, the part of the sleeve projecting into said cylinder having a sealing ring thereon, said sealing ring having a slidable fit in said cylinder, the end of said sleeve projecting into said cylinder being forced against the seating surface of said cylinder forming a seal around said contact member, a second grommet consisting of a sleeve of resilient material projecting in part into said tube

and in part into said connector, said sleeve of said second grommet having a flange determining the portions thereof extending respectively into said tube and connector, said flange being held between said tube and said connector, the end of said second grommet extending into said connector engaging the end of said first grommet extending into said connector, an insulated conductor extending through said second grommet into said first grommet, and means for making contact between the end of said conductor in said second grommet and said contact member.
